UNITED STATES PATENT OFFICE

147,599

DESIGN FOR A PORTABLE HAIR DRIER

Stanley R. Shields, Los Angeles, Calif., assignor of fifteen per cent to Charles R. Lucero, Los Angeles, Calif.

Application January 29, 1946, Serial No. 126,065

Term of patent 14 years

(Cl. D86—10)

To all whom it may concern:

Be it known that I, Stanley R. Shields, a citizen of the United States, residing at Los Angeles, in the county of Los Angeles and State of California, have invented a new, original, and ornamental Design for Portable Hair Driers, of which the following is a specification, reference being had to the accompanying drawing, forming part thereof.

Fig. 1 is a perspective view of a portable hair drier, embodying my new design.

Fig. 2 is a front view of the hood portion thereof.

Fig. 3 is a rear view of said hood portion.

I claim:

The ornamental design for a portable hair drier, as shown.

STANLEY R. SHIELDS.
